(57) **CLAIM**

The ornamental design for case for vacuum tubes, as shown and described.

DESCRIPTION

1. Case for vacuum tubes

1.1 : Perspective

1.2 : Front

1.3 : Back

1.4 : Left

1.5 : Right

1.6 : Top

1.7 : Bottom

1.8 : Reference

Reproduction 1.8 is a reference view showing a state of use in which a case for a vacuum tube caps a vacuum tube on a vacuum tube socket; the broken lines showing of a vacuum tube and a vacuum tube socket in reproduction 1.8 for the purpose of illustrating environmental structure form no part of the claimed design.
